UNITED STATES PATENT OFFICE.

EWALD ERNEST STURK, OF PORTLAND, MAINE.

TOY CANNON.

Application filed March 3, 1922. Serial No. 540,894.

To all whom it may concern:

Be it known that I, EWALD E. STURK, a citizen of the United States, residing at Portland, in the county of Cumberland and State of Maine, have invented certain new and useful Improvements in Toy Cannon, of which the following is a specification.

The present invention relates to a toy cannon and has for its principal object to 10 prove upon the structure shown in Letters Patent Number 1,358,125 issued to me on November 9, 1920. Another important object of the invention is to provide a novel spring hammer which is effective for improving 15 parting momentum to the projectiles so as to force them through the barrel of the cannon. Another object of the invention is to improve upon the projectile receptacle so as to provide the same with a slanting bottom 20 whereby the projectiles will be delivered to the rotary drum and properly aligned with the barrel of the cannon.

A still further object of the invention is to generally improve upon toy cannons of 25 this nature by providing a device which will be extremely simple and efficient in construction, reliable in operation, and well adapted to the purpose for which it is designed.

With the above and numerous other objects in view as will appear as the description progresses, the invention resides in certain novel features of construction, and the combination and arrangement of parts as 30 will be hereinafter more fully described and 35 claimed.

In the drawing:

Figure 1 is a side elevation of the toy cannon embodying my invention, a portion thereof being broken away so as to show the 40 interior of the barrel and the projectile casting.

Figure 2 is a transverse section taken through the device on the line 2—2 of Figure 1 looking in the direction of the arrows.

Figure 3 is a rear elevation of the device, a portion thereof being broken away.

Figure 4 is a transverse section taken substantially on the line 4—4 of Figure 3, and

Figure 5 is a detailed view showing the 50 construction of the rotary drum.

Referring to the drawing in detail it will be seen that the cannon is mounted on the wheels 1 by having their axles pass through the support 2 which may be designed in any 55 preferred manner so as to appear similar to the cannon having the trail 3. A cylindri-

cal receptacle 4 is mounted on the support 2 and a barrel 5. This barrel 5 is mounted so as to slide longitudinally of the cylindrical receptacle 4 which is open along its upper end as is shown in Figure 2 so that when the barrel is pulled forwardly projectiles may be passed through this opening into the receptacle. This receptacle is provided with an inclined bottom 6 which is substantially 60 V-shaped in cross section and leads to an opening 7 in the rear wall thereof. A rotary drum 8 is mounted on the bar 9 which is supported in the rear of the cylindrical receptacle 4 and is provided with a plurality 65 of annular arranged pockets which are adapted to be placed in registry with the opening 7 and the barrel 5 which are arranged diametrically opposite each other 70 preferably.

A spring hammer 11 is fixed at one end to the support 12 for the rotary drum 8 and is curved so as to form a loop 12 and an arm 13 extends upwardly therefrom. The bolt 9 passes through the arm 13 intermediate its 75 ends and also passes through a bow-shaped 80 spring 14 which has its ends bearing on the arm 13. The upper end of this bow-shaped spring 14 is formed with a pair of spaced offset lips 15 which embrace the arms 13 as 85 shown to advantage in Figures 3 and 4.

A series of teeth 20 are arranged in a circle on the drum 8 one tooth being situated adjacent each pocket in the drum as is indicated to advantage in Figure 3. These 90 teeth are provided with one slanting edge and one straight edge. The slanting edge is adapted to engage the hammer so as to force it away from the drum at its ends until it meets the straight edge when it is 95 released and will snap back to its original position and a lug 32 is provided on the hammer for projecting into the pockets of the drum so as to force a projectile therefrom and through the barrel 5. It will be 100 noted that a finger 33 extends from the upper terminal of the arm 13 for engagement with these teeth 20.

In order to rotate the drum I have fulcrumed a lever 35 on the bolt 9 so that the 105 same will be positioned between the bow-shaped spring 14 and the nuts 36 and this lever 35 extends through the guide frame 37 and is normally held in a horizontal position by a spring 38 which is attached to the support 12 by an eye bolt or in any other suitable manner. It will be seen that by de-

pressing the lever 35 the drum 8 may be rotated and when the lever is in a depressed position and is released the spring 38 will return it to its original horizontal position.

5 A consideration of the drawing bearing in mind the above description will readily enable anyone to understand the operation of the invention without a more detailed description thereof, but it is desired to point 10 out that numerous changes in form, proportion, and in the combination and arrangement of parts may be resorted to without departing from the scope of this invention as hereinafter claimed.

15 Having thus described my invention what I claim as new is:—

1. In combination, a container having a longitudinal opening in the top thereof, a barrel having a bore therethrough, slidably 20 mounted directly below and contiguous to the opening of said container, means for delivering projectiles from the container in alignment with the bore and means for forcing the projectile when in alignment with 25 the bore therethrough.

2. In combination, a container having a longitudinal opening in the top thereof, a barrel having a bore therethrough slidably mounted directly below and contiguous to the opening of said container, a longitudinal 30 bar mounted in the rear end of said container, and adapted to extend a substantial distance beyond the same, a rotary drum provided with a plurality of annular arranged pockets, mounted on said bar, a 35 spring hammer mounted on said bar, a bow-shaped spring mounted on said bar, the ends of said bow-shaped spring adapted to engage the spring hammer, an actuating means to rotate the bar mounted near the end of 40 said bore, said bow-shaped spring being situated on the bar between the spring hammer and the actuating means.

In testimony whereof I affix my signature in presence of two witnesses.

EWALD ERNEST STURK.
